(57) **CLAIM**

The ornamental design for a Christmas nativity display for game, as shown and described.

DESCRIPTION

FIG. 1 is a front elevational view of a Christmas nativity display for game showing my new design;

FIG. 2 is a top plan view thereof;

FIG. 3 is a bottom plan view thereof;

FIG. 4 is a right elevational view thereof;

FIG. 5 is a left side elevational view thereof;

FIG. 6 is a rear elevational view thereof; and,

FIG. 7 is another front view showing my new design in an environment of use.

The broken lines shown in FIG. 7 represent environmental subject matter and form no part of the claimed design.
